**COMBINED FIRST STAGE PRESSURE REGULATOR
AND A SHUTOFF VALVE FOR UNDERWATER
BREATHING APPARATUS**

Earl M. Shugarman, Costa Mesa, Calif., assignor to
W. J. Voit Rubber Corp., a corporation of California

Filed Aug. 5, 1964, Ser. No. 81,170

Term of patent 3½ years

(Cl. D83—1)

FIG. 1.

FIG. 2.

FIG. 3.

FIG. 1 is a perspective view of a combined first stage pressure regulator and a shut-off valve for underwater breathing apparatus embodying my new design;

FIG. 2 is a perspective view as seen from the opposite side of FIG. 1, and

FIG. 3 is a bottom plan view thereof.

I claim:

The ornamental design for a combined first stage pressure regulator and a shut-off valve for underwater breathing apparatus, substantially as shown.
